GEORGE W. LUDWIG, OF HOLLISOPPLE, PENNSYLVANIA.

SKELETON METALLIC SOLE FOR SHOES.

1,127,266.

Specification of Letters Patent.

Patented Feb. 2, 1915.

Application filed September 18, 1914. Serial No. 862,059.

To all whom it may concern:
Be it known that I, GEORGE W. LUDWIG, a citizen of the United States of America, residing at Hollsopple, in the county of Somerset and State of Pennsylvania, have invented 5 certain new and useful Improvements in Skeleton Metallic Soles for Shoes, of which the following is a specification, reference being had therein to the accompanying drawings.

This invention relates to skeleton metallic soles for shoes and has for its object to provide a sole of such class, in a manner as hereinafter set forth, which is adapted for use 15 for laborers, huntsmen and woodmen to prevent slipping.

A further object of the invention is to provide a skeleton metallic sole for shoes with means in a manner as hereinafter set forth for conveniently positioning and removing the sole from a shoe when the occasion so requires.

A further object of the invention is to provide a skeleton metallic sole for shoes which 25 is simple in its construction and arrangement, strong, durable, efficient in its use, and inexpensive.

With the foregoing and other objects in view, the invention consists of a novel construction, combination and arrangement of parts as hereinafter more specifically described and illustrated in the accompanying drawings wherein is shown an embodiment of the invention, but it is to be understood, 35 that changes, variations and modifications can be resorted to which come within the scope of the claims hereunto appended.

In the drawings wherein like reference characters denote corresponding parts throughout the several views:—Figure 1 is 40 an elevation, in full and dotted lines, of a skeleton metallic sole in accordance with this invention, showing the adaptation thereof in accordance with a sole, the sole 45 being indicated in dotted lines. Fig. 2, is an elevation of a skeleton metallic sole in accordance with this invention of a modified form, showing the adaptation thereof in accordance with a sole of a shoe, the latter 50 shown in dotted lines. Fig. 3, is an elevation of a shoe showing the adaptation therewith of a skeleton metallic sole in accordance with this invention.

Referring to Fig. 1 of the drawings the 55 skeleton metallic sole is formed of a single length of corrugated wire of the desired

eligibility and consists of a series of transverse extending loops connected together intermediate their ends and the connection between one pair of loops is staggered with respect to the adjacent pair of loops. The 60 connection between the loops is indicated at 2. The transverse loops at the forward end of the sole are connected together by a coupling 3, which terminates into an adjusting 65 member 4, the latter terminating in a forward transverse loop 5. One of the transverse loops intermediate the ends of a sole is extended at each end to form a pair of adjusting members 6, 7. The rear transverse 70 loop 8 of the sole terminates in a pair of rearwardly extending portions 9, 10, which are connected together by a sleeve 12, and the said portions 9, 10, terminate into loops 13, 14, which terminate into forwardly projecting attaching arms 15, 16.

The modified form shown in Fig. 2 is constructed similar to that shown in Fig. 1, but with this exception, that the wire is straight and not corrugated. The modified 75 form of sole illustrated in Fig. 2 is indicated by the reference character 17, its loops at 18, its attaching members at 19, 20, 21, and its attaching arms at 22, 23. The attaching members 19, 20, 21, and adjusting 80 arms 22, 23, and the attaching members 4, 5, 7 and adjusting arms 15, 17 are constructed in a manner whereby they will overlap the top of the sole 24 of the shoe 25. The 85 adjusting member 4 or 19 is adapted to abut against the end of the sole 24 at the toe portion thereof as well as overlap the toe portion. The adjusting members 4, 21 or 6, 7 are adapted to engage the sides of the sole and overlap as well as engage the top thereof and the adjusting arms 15, 16 or 22, 23 are adapted to engage the side edges of the sole 24 and overlap the top of the sole at the rear thereof, that is at the beginning of the arch.

The material from which the skeleton sole is constructed is efficiently resilient whereby when the adjusting members or arms engage with the sole on the shoe, the skeleton sole will be firmly held in position and be 95 prevented from slipping off from the sole of the shoe.

What I claim is:—

1. A skeleton metallic sole consisting of a body portion formed from a single length 100 of wire bent to provide transversely extending connected loops arranged in spaced re-

lation, said body portion further having at its rear a pair of adjustable arms capable of gripping the sole of a shoe, certain of said loops of said body portion being extended to provide attaching members capable of gripping a sole of a shoe for connecting, in connection with said arms, said body portion to the sole of a shoe.

2. A skeleton metallic sole consisting of 10 a body portion formed from a single length of wire bent to provide transversely extending connected loops arranged in spaced relation, said body portion further having at its rear a pair of adjustable arms capable of 15 gripping the sole of a shoe, certain of said loops of said body portion being extended to provide attaching members capable of gripping a sole of a shoe for connecting, in connection with said arms, said body portion to the sole of a shoe, the material forming said body portion being corrugated from end to end.

3. A skeleton metallic sole consisting of a body portion formed from a single length

of wire bent to provide transversely extending connected loops arranged in spaced relation, said body portion further having at its rear a pair of adjustable arms capable of gripping the sole of a shoe, one of said loops being extended to provide a pair of adjusting members and another of said loops being extended to provide a single adjusting member, said single adjusting member being capable of overlapping the sole of a shoe at the toe and said pair of adjusting members being capable of overlapping the sole of a shoe at the side thereof and said adjusting members in connection with said arms being connected to be detachably secured to said body portion and the sole of a 40 shoe.

In testimony whereof I affix my signature in the presence of two witnesses.

GEORGE W. LUDWIG.
